UNITED STATES PATENT OFFICE.

MOSES J. DAVIS, OF PUEBLO, COLORADO.

VENTILATING SANITARY SEAT-CUSHION.

1,181,575.

Specification of Letters Patent. Patented May 2, 1916.

Application filed October 20, 1913. Serial No. 796,314.

To all whom it may concern:

Be it known that I, MOSES J. DAVIS, a citizen of the United States, residing at Pueblo, in the county of Pueblo and State of Colorado, have invented a new and useful Ventilating Sanitary Seat-Cushion, of which the following is a specification.

The device forming the subject matter of this application is a cushion, adapted to be applied to the seat or the back of a chair, bench, settee, or the like, for the purpose of affording a ventilation, either along the back or along the seat.

One object of the invention is to provide a cushion of the type above indicated comprising an air space, means being provided whereby access may be had to the air space.

Another object of the invention is to provide novel means for holding the seat of the cushion in place.

The invention aims further to provide a device of the type above indicated which may be adjusted readily to conform to the backs and seats of chairs, benches or the like.

It is within the scope of the invention to improve generally and to enhance the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing:—Figure 1 shows in front elevation, one form of the invention; Fig. 2 is a rear elevation of the structure shown in Fig. 1; Fig. 3 is an end elevation of the structure shown in Fig. 1; Fig. 4 is a side elevation of the structure shown in Fig. 1.

In carrying out the invention, reference being had to Figs. 1, 2, 3 and 4, there is provided a support which is a composite structure. The support includes a resilient inner frame 1, of U-shape, the ends of the frame 1 being connected by a turn buckle 2. The inner frame 1 is provided with legs 3 defining openings 4. Flexible transverse straps 5 extend across the ends of the legs 3, the ends 6 of the straps 5 being overlapped

upon the inner frame 1. As shown in Fig. 3, one of the straps 5 may be engaged by the turn buckle 2, there being nuts 50 on the turnbuckle which engage the inner face of the frame 1, and there being nuts 51 on the outer ends of the turnbuckles which, coacting with the ends of the straps, serve to hold the said strap against the outer face of the frame 1.

The support further includes a resilient U-shaped outer frame 7 which is superposed upon the inner frame 1. The inner face of the auxiliary frame 7 is beveled as indicated at 8 to receive a ventilating seat 9 which extends across the edge of the outer frame 7. The seat or filler 9 may be fashioned from wire netting, although any other material may be employed if deemed expedient. As shown at 10, the periphery of the seat 9 is bound between the frames 1 and 7.

Securing devices 10 connect the frames 1 and 7, these securing devices preferably being in the form of bolts carrying nuts 12 which are located in the openings 4 of the inner frame 1. The device as above described is adapted to be applied to the seat of a chair, although, should occasion demand the structure may be applied to the back of a chair, the contour of the frames 1 and 7 being altered by adjusting the turn buckle 2, to the end that the device may conform properly to the seat or the back of a chair.

When the chair is provided with a cushion, the straps 5 serve to prevent the cushion from being pressed upwardly or outwardly, within the contour of the frames 1 and 7. Thus, the air space existing within the frames 1 and 7 is not encumbered, and air is permitted to pass through the openings 4 in the inner frame 1, the open mesh ventilating seat 9 serving to permit the body of the occupant to remain cool. Although the element 9 has been described as a seat, it will be obvious that the same may constitute a back, if the structure shown in Figs. 1 to 4 inclusive is placed upright in a chair. In case the chair to which the device is applied is not provided with a cushion, then it may be desirable to dispense with the straps 5.

Having thus described the invention, what is claimed is:—

In a device of the class described, a resilient U-shaped inner frame embodying arms and provided on its lower edge with

spaced legs defining openings therebetween; straps disposed transversely of the inner frame and extended across the lower edges of the legs, upwardly along the outer faces of the legs and having their ends disposed on top of the inner frame; a turnbuckle extended through the free ends of the arms; pairs of nuts on the turnbuckle, one pair of nuts bearing against the inner faces of the 10 arms, the other pair of nuts bearing against one of the straps to hold the same against the corresponding legs; a resilient U-shaped outer frame superposed on the inner frame; a foraminous seat extended across the upper 15 edge of the outer frame, the seat being prolonged downwardly on the exterior of the outer frame and having its periphery extended between the frames on top of the

ends of the straps; bolts passing both frames, whereby both frames may be expanded and contracted at once by means of the turnbuckle, and whereby the frames will constitute clamping means adapted to hold the ends of the straps and to hold the periphery of the seat; and nuts on the lower 20 ends of the bolts and located in the openings, the nuts engaging the lower edge of the inner frame between the legs thereof.

In testimony that I claim the foregoing as my own, I have hereto affixed my signature 25 in the presence of two witnesses.

MOSES J. DAVIS.
